US0D1078040S

(12) **United States Design Patent** (10) Patent No.: **US D1,078,040 S**
(45) Date of Patent: ** Jun. 3, 2025

(54) **CASSETTE FOR DRUG DELIVERY ACTUATOR**

(71) Applicant: **Enesi Pharma Limited**, Abingdon (GB)

(72) Inventors: **Owen Ryan**, Wicklow (IE); **David Andrew Grant**, Faringdon (GB); **Ritwik**, Harwell (GB)

(73) Assignee: **Avaxzipen Limited**, Abingdon (GB)

(**) Term: **15 Years**

(21) Appl. No.: **35/517,506**

(22) Filed: **Jun. 15, 2022**

(80) **Hague Agreement Data**

Int. Filing Date: **Jun. 15, 2022**

Int. Reg. No.: **DM/225295**

Int. Reg. Date: **Jun. 15, 2022**

Int. Reg. Pub. Date: **Jun. 16, 2023**

CLAIM

The ornamental design for cassette for drug delivery actuator as shown and described.

DESCRIPTION

1.1 is an enlarged front view of a cassette for drug delivery actuator showing the design;

1.2 is a top and front perspective view thereof;

1.3 is a left side view thereof;

(Continued)

- 1.4 is a bottom view thereof;
- 1.5 is a right side view thereof;
- 1.6 is a top view thereof;
- 1.7 is a top and right side perspective view thereof; and
- 1.8 is a top and left side perspective view thereof.

1 Claim, 8 Drawing Sheets
